UNITED STATES PATENT OFFICE.

WILLIAM H. GINDER, OF HADDONFIELD, NEW JERSEY, ASSIGNOR, BY MESNE ASSIGNMENTS, TO ELECTRO MANUFACTURING COMPANY OF AMERICA.

PORTABLE FAN.

Application filed January 9, 1928. Serial No. 245,383.

This invention relates to portable fans, with particular reference to those fans projecting a horizontal stratum of air radially from the source.

5 Among the objects of this invention are; to improve the construction of fans; to provide a neat and attractive fan at a low cost; to reduce the labor normally necessary in assembling and finishing fans; to provide an 10 efficient but substantially silent fan by structural improvements therein; to provide a fan susceptible to adjustment and repair without material disassembly of the fan; to provide an assembly of fan, guard and 15 deflector which is susceptible to quick and easy assembly or disassembly, but which is rigid and firm in its assembled unitary condition; to provide as elements of a fan assembly, preformed units, the subject of machine 20 operations; to improve the guard constructions of fans; and many other objects and advantages as will be more apparent as the description proceeds.

In the accompanying drawings,

25 Fig. 1, represents a vertical section through an assembled fan according to this invention, partially in elevation,

Fig. 2, represents a section on line 2—2 of Fig. 1,

30 Fig. 3, represents a bottom elevation of the fan with the bottom plate removed to show the inner assembly, and

Fig. 4, represents a fragmentary section through the fan, with the motor in elevation 35 to show the mounting of the motor in the base shell.

The base of the fan comprises a hollow shell 10, preferably stamped or spun to form a truncated hollow cone, having the flaring 40 enlarged skirt 11, and the substantially flat or plane top 12, in which an axially concentric opening 13 is formed of such diameter as to afford a sliding but guiding engagement with the axially inserted motor 45 to be described. Inwardly formed in the skirt of the shell at desired points thereon are the angular brace members 14, having each a lower flat face 15, substantially parallel with the plane of the lower or bottom 50 edge of the skirt, but spaced slightly thereabove to form a plate receiving recess within which a plate 16 is mounted, with its lower face in substantial alignment with the lower edge of the skirt. The plate is at-

tached to the angular brace members by 55 means of bolts 17 passing through the plate and into threaded openings 18 formed in the faces 15 of the brace members. The angular brace members are attached to the shell in any desired manner to form rigid braces, 60 as by soldering or welding, although it will be obvious that it is perfectly permissible to strike them from the material of the shell as integral portions thereof, (not shown), and this formation of the braces is con- 65 sidered within the purview of the invention.

Motor arms 20 are provided, preferably comprising a pair of arms diametrically disposed on opposite sides of the shell comprising each a substantially vertical shank 21, 70 and a substantially radially inwardly extending foot 22 spaced above the lower edge of the skirt and in a plane parallel therewith. Each motor arm is rigidly attached to the inner surface of the shell as by soldering or welding, although it may be struck from the material of the shell if desired. Suitable pads of cushioning material, (not shown) may be mounted on the feet, and the feet are each formed with a bolt hole 80 through which motor bolts may be extended as later described. It will be observed that although the vertical shanks of the motor arms are laterally disposed relative the axis of the shell so as to be out of the path of 85 the axially inserted motor to be described, yet the feet of the arms extend inwardly so as to register with the opening 13, being thus in the path of movement of the axially inserted motor.

A fan guard is provided to form a rigid and substantially immovable unit with the shell comprised of a plurality of arms, preferably three in number, although this may be varied as desired, each including vertical 90 posts 24, curved at their lower ends to form shell arms 25 converging upon and rigidly affixed to the shell at points spaced from the opening 13 therein. The shell arms of the guard may be fastened as desired to the shell, 100 and it is preferred that the terminals thereof be reduced and threaded with a shoulder 26 arranged for direct engagement with the outer wall of the shell, or by an interposed washer, with the threaded shank 27 extending through an opening 28 in the shell, and fastened in place by a washer 30 and nut 31. If desired this removable connection may be

replaced by a soldered or welded connection. It is to be noted that the arms form a sharp bend 32 at the juncture of the posts 24 and arms 25, which bend is spaced vertically 5 above the upper end of the shell and forms the lower boundary of the guard. A pair of annular forming members 33 and 34 of substantially identical diameters are provided, to which a short cylinder of perforated sheet metal 35 is affixed, as by soldering or welding, and which members delineate the upper and lower extremities of the guard. A sheet of screen or mesh material 36 having a concentric axial opening 37, slightly larger than 10 the opening 13 of the shell, is soldered or welded to the lower annulus or forming member 34, with the central opening finished by an annulus 38 soldered or welded to the mesh material to strengthen the lower face 15 of the guard, and impart an ornamental finish to the mesh material, and to form a smooth guide through which the subsequently attached motor may slide without interference. The mesh material is preferably of such gauge that the vertical posts 20 may be extended through the mesh on the inner surface of the cage defined by the forming members 33 and 34 and the cylindrical sheet metal 35, and be attached thereto 25 in a rigid unit as by soldering or welding, to form a rigid unit with the shell, as will be clear.

The upper ends of the vertical posts 24 terminate each in axially inclined radially 30 extending flattened lugs 40, having an opening, and upon which the removable deflector 41 is mounted. The deflector comprises a downwardly extending concentric hub 42, a concentric curved surface 43 falling sharply 35 away from the hub and terminating in a substantially horizontally projecting surface 44. The curvature is preferably an irregular curve so that the angle at the hub is more pronounced than it is remote from the hub, to afford clearance space above the fan blades to 40 prevent the turbulence and noise incident to crowding the air between the fan blades and the deflector. The deflector is preferably a shell which may be stamped or spun as desired, and may have a concentric plug 45 disposed above the hub to impart a more ornamental appearance or finish to the fan. Near the outer periphery of the shell on the lower surface thereof, short bolts 46 are extended, arranged for registration with openings 46 in the lugs 40 on the ends of the vertical posts 24, to which lugs the deflector 41 is affixed by nuts 47, or in any desired manner. It will be seen that as described the 50 deflector shell is rigidly mounted on the ends of the vertical posts, but is susceptible to quick removal axially away from the shell and guard. The unit so far described is in its assembled condition, a rigid whole.

60 An electric fan motor of any desired sort

but preferably comprised of a cylindrical casing 48 arranged for vertical positioning and operation, is formed preferably although not necessarily with shoulders or recesses 50, arranged to seat upon the feet 22 70 of the motor arms of the shell, and to be rigidly affixed thereto by vertically extending bolts 23. As noted cushioning pads may be mounted on the feet prior to the attachment of the motor. The motor is of substantially the same diameter as the opening 13 in the shell so that the motor, axially inserted through the annulus 38 of the guard has a sliding engagement with the edge of the shell formed by the opening 13, in which it is 80 guided to rest upon the motor feet, and by which it is laterally supported at the top of the shell. The motor is thus maintained in fixed position by cooperation between the feet of the motor supports mounted on the 85 shell, and the shell itself. This effects a rigid assembly for the motor and shell, and it will be clear that if desired cushioning materials of any desired sort may be interposed between the periphery of the motor 90 casing and the edge of the shell to absorb vibrations from the motor or fan blades to quiet the fan, although this will not ordinarily be necessary.

The upper end of the motor is provided 95 with brush changing lugs or nuts 51, vertically disposed above the upper portion 12 of the shell, but disposed vertically below the lower surface of the fan guard, and extending laterally from the motor in the clearance maintained between the guard and the shell for manual actuation of the nuts and the changing or adjustment of the brushes without disassembling the motor or the supporting and housing structure in which it is 100 disposed. As the brushes are usually the only points requiring adjustment and repair it will be seen that the manipulations necessary to the end may be consummated without disturbing the fan assembly.

The motor 48 is provided with a lower journal 52 and upper journal 53 extending perpendicularly from the respective end faces of the motor. The end faces are provided with a plurality of ventilating openings 54 through which air passes to cool the motor. The upper journal has an opening through which the armature shaft of the motor extends within the space defined by the guard of the fan, when the motor and unit are assembled. The shaft 55 of the motor is arranged to receive the axially bored hub 56 of the fan blades 57, to which the hub is affixed by such means, for instance, as a set screw 58. It will be observed 110 that the fan blades are attachable to the motor by a simple axial movement after the motor is in place in the shell. It will further be observed that although the hub of the deflector is immediately adjacent the hub 115 120 125 130

of the fan blades yet the curvature of the deflector is such that as the air stream becomes stronger, as it does as the point of observation is further from the axis of the fan, clearance is afforded by the space indicated by numeral 60 enabling the airstream to get clear of the fan before being subjected to the turning action of the deflector, resulting in a minimized noise and efficient 10 functioning that otherwise may not occur.

It will be observed further that the channel for the radially projected horizontal air stream defined between the edge of the deflector and the upper edge of the guard is 15 of substantially the same vertical extent as the guard itself, resulting in an improved ornamental appearance.

Assuming the formation of the separate units involved in the invention, as the shell 20 base, the guard, the deflector, the motor and the fan blades, it will be clear that the actual labor involved in the assembly of the fan is a minimum. The shell and guard are first formed into a unit. The motor is then 25 inserted axially through the annulus 38 of the guard, through the opening 13 in the top of the shell to seat its shoulders or recesses 50 upon the inwardly projecting feet of the motor arms. This assembly is then made 30 rigid by extending the bolts 23 through the appropriate holes in the feet of the arms and into the motor. The fan blades are then axially attached upon the perpendicular motor shaft and fastened by the set screw. 35 The deflector is axially mounted upon the upper ends of the vertical posts, and fastened by the nuts on the bolts thereof. It will be understood that appropriate wire aperture 61 and switch aperture 62 will be 40 formed in the shell during its construction to permit of the lateral insertion of lead wires 63, although obviously the lead wires may be inserted otherwise as desired, as through the bottom for instance, and toggle 45 switch 64 for controlling the motor circuits. It will be clear that there is ample clearance between the lower end of the motor and the bottom plate to permit manipulations necessary to establish the connections. The 50 plate 16 may be added at the conclusion of the assembly operation, by bolts 17 extending into the threaded openings 18 in the lower flat faces of the angular brace members. It will be understood that the lower 55 plate may carry elastic or other studs 65 to form a non-scratching frictional support for the fan, and to raise the fan sufficiently to enable air to pass under the plate 16 and through appropriate openings in the plate as 60 intake ports for the air drawn through the openings 54 in the end faces of the motor 48.

The invention herein disclosed effects a quiet, ornamental, efficient portable fan at a 65 reasonable and economical cost, both for the

initial production costs, and for repair and upkeep expenditures.

I claim as my invention:

1. In a portable fan, a shell, having an upper opening, motor support means mounted in the shell below the opening, a motor of substantially the same diameter as said opening guidable slidably through said opening and engaging the support means, said motor extending above said shell and the 70 shell at the opening forming a lateral support for the motor.

2. In a fan of the class described, a shell, the shell having a reduced upper portion having a concentric opening therein, the 80 lower portion of the shell having a flared skirt, a motor frictionally mounted in the opening to extend thereabove and held against lateral movement by the material surrounding the opening, motor supports 85 extending from the inner surface of the shell to engage the motor and maintain it rigidly against vertical movement spaced above the skirt of the shell, the flare of the skirt enhancing the ornamental appearance 90 and stability of the shell base and also delineating clearance space beneath the motor in which wiring connections may be established.

3. In a fan, a support and housing comprised of a shell having an opening, a guard mounted on the shell close to but spaced from the opening vertically, the guard including a lower apertured sheet having an opening concentric with the opening in the shell, a motor supporting arm disposed in the shell having a portion in registry with the openings, a motor axially insertable through both openings to seat upon the registering portion of the motor support, the 95 motor having a shaft extending perpendicularly above the lower apertured sheet of the guard, and having brush changing elements laterally extending from the motor and disposed in the space between the guard and 100 the upper portion of the shell whereby said elements may be manipulated without disassembling the motor, guard and shell assembly.

4. In a fan, a housing, a motor disposed in the housing with a portion extending above the housing, brush changing elements carried on said portion, a guard comprised of a cylindrical body and a horizontal sheet of mesh material disposed above the end 115 of the motor and housing but spaced from the housing, arms connecting the guard to the housing at points close to but spaced from the motor, the arms being spaced apart such distances as to enable manipulations of 120 portions of the motor disposed in the space between the fan guard and housing.

5. In combination a shell having an opening, a guard including curved arms removably but rigidly affixed to the shell adjacent 130

to but spaced from the opening, said guard having an axially concentric opening spaced above the opening in the shell, a motor axially mounted in the shell in the opening 5 therein having a portion extending through the opening in the guard, brush changing elements mounted on the motor in the vertical space between the openings in the shell and guard to permit manipulations thereof 10 without disturbing the assembly, and a fan blade unit mounted on the portion of the motor extending through the opening in the guard, and an axially mounted curved deflector removably mounted on the guard in 15 proximity to the fan blade unit in position to deflect the upward flow of air in a substantially horizontal stratum, the deflector and fan blade unit being each axially removable to permit the axial removal of the 20 motor without affecting the assembly of the shell and guard.

6. In combination in a fan, a hollow shell, motor supports disposed in the shell

mounted on an inner surface thereof, the shell having an opening in registry with the 25 motor supports, a substantially vertical motor mounted in the opening of the shell upon the supports, having vertical air passages for ventilating the motor, a fan blade mounted on the motor for rotation with parts thereof to draw a circulating air stream through the motor, lugs mounted on the shell near the base thereof, a plate, having an opening, mounted on the lugs substantially in the plane of the 30 lower portion of the shell, and lugs forming a support for the plate and shell to maintain an air space beneath said plate whereby the circulating air stream may be drawn through the opening in the plate in 35 its passage through the motor.

Signed at Philadelphia, county of Philadelphia, State of Pennsylvania, this 6th day of January, 1928.

WILLIAM H. GINDER.
